UNITED STATES PATENT OFFICE.

JAN ZALIKOWSKI, OF CHICAGO, ILLINOIS, ASSIGNOR OF THREE-FOURTHS
TO AUGUST J. KOWALSKI, THEODORE LEWANDOWSKI, AND ANDREW
SCHULTZ, OF SAME PLACE.

WINDOW CASING AND SASH.

SPECIFICATION forming part of Letters Patent No. 402,708, dated May 7, 1889.

Application filed August 8, 1888. Serial No. 281,910. (No model.)

To all whom it may concern:

Be it known that I, JAN ZALIKOWSKI, a citizen of the United States, residing at Chicago, in the county of Cook and State of Illinois, have invented a new and useful Improvement 5 in Window Casings and Sashes, whereby windows may be readily swung or turned into position for cleaning, &c.; and I do hereby declare that the following is a full, clear, and 10 exact description of the invention, which will enable others skilled in the art to which it appertains to make and use the same.

My invention relates to window casings and sashes.

15 The object of my improvement is a provision whereby window-sashes having panes of glass therein may be readily adjusted in position more favorable for cleaning, washing, repainting, or repairing generally than when the 20 sashes are fastened in the ordinary manner.

My invention consists in the combinations of elements embraced in the claims.

In the accompanying drawings, Figure 1 is a front view of the window casing and sashes embodying my invention, the casing being partly 25 sectional, as also a lower corner of the lower sash. The vertical section-line of the left-hand side of the casing passes through the fastenings of the inside stop or the inner window- 30 strip, in order to show the connection of the said fastenings. The vertical section-line on the right-hand side of the casing is partly within the plane of the inside portion of the lower window-sash to show the relation of the 35 said sash to its pulleys and weights, and partly within a plane of the sash-cord groove and the sash-weight chamber to show the weight, pulley, and cord and the hinge-connection at the lower corner of the sash. Fig. 2 is another 40 vertical sectional view taken on a line. That on the left side passes through the parting-bead or separator-strip between the sashes, and on the right side passes through the pulley, the groove in the casing for the cord, and 45 the sash-weight chamber. Fig. 3 is a vertical section of the window casing and sashes with connecting parts, taken on a vertical line just at the right of the upper left side pulleys, the journal parts of the hinge-connections being 50 shown in section. Fig. 4 is a vertical section on a line of a plane immediately at the right

edges of the sashes, the lower parts of the inside stop and the parting-bead (that are removable, as hereinafter described) not being represented, but the places for their insertion 55 being shown, and the sashes being represented in dotted lines as turned down in horizontal position. Fig. 5 is a horizontal section broken away, taken on a line, 5 5, Fig. 3, passing through a portion of the upper or spring-bolt 60 fastening for the inside stop or inner removable strip, and showing in section parts of the hanging stile, the inside sash, the outside sash, the inside stop, the parting-bead, the blind-stop, the weight-chambers, and weights 65 therein. Fig. 6 is a vertical broken-away sectional view of the right lower corner of the window-casing and lower sash, a part of the lower right-hand corner of the sash being 70 broken away to show the hinge-connection thereof and its chain for supporting the said sash. Fig. 7 is a vertical cross-section taken on the line 7 7 of Fig. 6, through the hinge-connection therein shown, the sash part being shown in dotted lines as turned down in a 75 horizontal position. Fig. 8 is a bottom view of the same hinge-connection and corner of sash, taken on line 8 8 of Fig. 6. Fig. 9 is a horizontal section through the upper fastening of the inside stop or strip, taken on line 5 5 of 80 Fig. 3, showing the spring-bolt with its bottom turned in horizontal position, holding the inside stop locked with the hanging stile. Fig. 10 is an illustration of a modification of the hinge-connection when the sash is in an up-right position and looking toward the inner 85 face of said sash. Fig. 11 is an illustration of the same looking toward the edge of the sash, dotted lines showing the sash turned down.

Similar letters refer to similar parts 90 throughout the several views.

A is the window-casing.

B is the upper window-sash.

C is the lower window-sash.

D are the removable parts of the inside 95 stops or inner strips, E, for the inside or lower sash.

F are the removable parts of the parting-beads or separating-strips F'.

G G' are socket-pieces in the form of plates 100 secured to the sides of the window-casing.

H are springs so placed that they shall

press against the sides of the removable parts F of the parting beads or strips F' when said parts F are placed in position for holding the outer or upper sash in the casing.

5 I are thumb-bolts for fastening in position on the window-casing the removable parts D of the inside stops or inner window-strips.

J are plates on the removable parts D of the inside stops or inner removable strips, 10 provided with lugs j for assisting in fastening the said removable parts D.

L are recesses in the socket-pieces G, for the catch-pieces of the thumb-bolts I to pass into in locking their ends.

15 L' are recesses in the socket-pieces G', for the lugs j of the plates J to pass into in catching fast.

M are holes in the upper ends of the removable parts D, for the shank of the thumb-bolts I to pass into and work within.

N is one form of pivotal connection for hinging the sashes at their lower corners.

O is another form of pivotal connection.

10 O' are plates attached to the bottom of each 25 sash.

P are rope (or chain) sockets having journal-bearings near their lower ends.

Q are springs secured within the rope socket-pieces P.

30 R are staples driven into the window-casing and also into the front parts of the sashes to form loops; or they may be loops or rings having screw-shanks attached thereto.

S are the sash-cords.

35 T are the sash-weights.

U are the pulleys over which the cords run.

V are the lower ends of the removable parts F of the parting-bead.

W and W' are the upper ends, respectively, 40 of the parts D and F.

X are the rope or chain fastenings in the rope-socket P.

Y are the rope or chain fastenings, forming a modification.

45 The various parts of the construction are formed with the view of being operated by letting the sashes down near the bottom of the window-casing and then their tops out into the room at right angles, cords being at-

50 tached in staples or hooks on the casing and on the sashes to hold up the inner ends of said sashes, the other ends being designed to turn on pivotal connections in the window-casing, without the sashes being entirely re-

55 moved therefrom—that is, the pulley cords, ropes, or chains (whichever may be used in connection with weights to balance the window-sashes) are not to be detached in order to turn out the tops of the sashes into position

50 for washing and cleaning the window-panes of glass or doing other work upon the window-sashes that could be more safely or readily performed than when they occupy their regular vertical position in a window-easing.

55 The inner parts of the grooves in the casings

are of a depth corresponding to the requirements of the ropes, cords, or chains, as the case may be. If a flat chain be used, said grooves may be comparatively shallow. Moreover, the 70 said grooves are of less width than the edges of the sashes, so that the sashes do not enter them, and hence leave the chains free to run therein. The pulleys are well set back in the window-casings, so as to allow the chains or 75 cords running over them to pass directly down in the grooves without being pressed upon by the sashes.

The hinge-connection is formed in either of two ways, either in the form of a rope-socket 80 having near its inner end a journal-bearing, as shown in Figs. 1, 6, and 7, or in the form of a ring, as shown in Figs. 10 and 11, the rope-socket piece or the ring, as the case may be, being secured to the end of the sash sustaining and balancing rope or chain, and the journal-bearing in the one case, or the ring attached to a rope or chain in the other case, serving to receive a pivotal piece or journal secured by its plate O' to the bottom of the 90 sash at the lower corner thereof.

The plate O', as shown in Fig. 8, is secured by screws to the bottom of each sash at each of its lower corners, and is provided with a journal part or pivotal piece, o', having a cam, 95 o². The sash, when turned to a horizontal position within the room, as shown in dotted lines, Fig. 7, causes the cam o² to be firmly pressed against a leaf-spring, Q, secured at its other end (at x) to the inner part of the socket 100 P, causing the spring to press its lower end, p', firmly against one of the inner walls of the groove in which the socket-piece P and its cord travel, thus temporarily fastening the hinged end of the sash, so that its weights cannot raise it until the window-sash has again been turned back into its normal upright position.

In the modified form of the pivotal connection shown in Figs. 10 and 11 the cam o² is 110 intended to be of sufficient height to avail in binding itself within the cord-groove, upon the sash being turned down, without the use of a spring; or, if a spring is used, it may be one fastened within said groove in a position 115 to be pressed upon by said cam at that time to assist in fastening down the sash, as also serving to protect from wear and injury the side of the cord-groove that the cam o² turns against.

120 In Figs. 6 and 7 the sash-chain is fastened at X by means of a rivet or bolt passing through the lower link of the chain and into holes in the socket-piece P.

In Figs. 10 and 11 the chain terminates in 125 a ring that surrounds the journal part o' of the plate O', forming the fastening Y.

As shown in Figs. 1, 6, and 7, the rope-socket pieces pivotally connected to the lower window-sash are extended somewhat below their 130 journal-bearings, recesses p² being formed in the window-sill to receive the said projecting

parts when the said sash is lowered to its farthest extent. This provision is to admit of that sash turning down at a lower pivotal point than the upper sash, so that the latter 5 may turn down readily over the other after it has been turned down in horizontal position.

The window-strips are each made in two parts, the upper parts being securely affixed in their places, while the lower parts are provided with means for readily securing them and releasing them at will, as it is only by removing said lower parts that the way becomes clear for swinging or turning down the window-sashes after they have been lowered 15 to their extreme limits, as shown.

Staples or rings R may be secured in the casing and also in the sashes, in which cords may be fastened for sustaining the sashes in horizontal position, and thus obviating strain 20 on the pivotal connections.

The thumb-bolt I, used for fastening and unfastening the top portion of the removable part of the inside stop, E, is formed of several parts, as follows: The screw-threaded 25 bolt i is provided at its inner end with a button, i' , and with a spring, i^2 , nut i^3 , and hollow knob i^4 . The knob i^4 is so connected at its base with the bolt i that the latter may be longitudinally reciprocated in the opening in 30 the bottom of the base, but must turn with the knob. This is provided for by squaring that portion of the bolt's shank having a bearing in said opening and squaring the opening to correspond. A groove and spline 35 may serve the same purpose as squaring the parts, and various other means for causing the two parts to rotate with each other may be employed. The nut i^3 fits loosely within the outer hollow portion of the hollow knob 40 i^4 , its inner end bearing against the outer end of the spring i^2 , and the latter's inner end bears against the inside of the bottom of the knob i^4 , the spring i^2 surrounding a portion of the bolt i , and by the construction 45 being practically inclosed from view. The spring constantly tends to press outward the nut i^3 , and thereby draw the bolt outward as far as its button i' will admit. The bolt works in the hole M of the removable part D 50 of the inside stop, as shown in Figs. 1 and 9, and its button i' is drawn snugly up against the inside of the removable part D when the latter is not in use. When, however, the said part is used, the thumb-bolt I then comes 55 into play, and the button i' , after having been passed into the recess of the socket-plate G, is then turned a quarter-turn, when its spring i^2 forces it, by means of its attached bolt i and nut i^3 , tightly up against the inside surface of said socket-plate.

The rope-socket pieces P are usually of different lengths below their points for the journal-bearings therein, according as they are placed on the inside or lower sash or the 65 outer or upper sash, the longer lower projections being used on the latter in providing

that its pivotal point shall be higher than that of the other sash. However, if the recesses p^2 for the lower projections of the rope-socket pieces P, used on the inside sash, were 70 made sufficiently deep in the sill, then all the said rope-socket pieces could be made of like lengths.

The upper end, W, of the removable part D of the inside stop and also the upper end 75 of the removable part F of the parting-bead terminate with inclines that correspond with inclines on the contiguous fixed portions of the respective strips. These inclines mark the points of separation between the parts of 80 the inside stop, E, and the parts of the parting-bead F'.

When it is desired to turn out into the room the tops of the sashes, the parts D and F are removed, the spring H, bearing against the 85 side of the part F, offering only slight frictional resistance to slipping out the part F, and the part D being unlocked by a quarter-turn of the thumb-bolt I. The part F is lifted out of the recess V after the upper portion of 90 the part F has been withdrawn from the recess in the casing in which it is held. The lug of the plate J is readily withdrawn from the recess L' of the socket-plate G' after the thumb-bolt I has been detached from the 95 socket-plate G. The button i' of the bolt i is readily disengaged from the socket-plate G' by pressing inward on the nut i^3 , thus overcoming the resistance of the spring i^2 , and then turning the nut i^4 until the button is in 100 position to be withdrawn through the opening or recess L in the socket-plate G. It is preferred to remove the parts D and turn down inside of the room the inside or lower sash on its pivots, then remove the parts F and lower 105 sash and turn it down on its pivots.

The sashes are turned up and back in the reverse order and the fastening-strips F and D replaced in their positions for assisting in maintaining them in their vertical position, 110 whereupon the sashes may be vertically reciprocated and used, generally, as in the case of ordinary window-sashes.

Having thus fully described my invention, what I claim, and desire to secure by Letters 115 Patent, is—

1. A spring thumb-bolt, I, consisting of the screw-threaded bolt i , having button i' , spring i^2 , nut i^3 , and hollow knob i^4 , in combination with the removable strip D, the plate J, having lug j , and the casing having socket-plates G G', substantially as and for the purpose described.

2. The rope-socket piece P, provided with the spring Q, in combination with the journal 125 o' and its cam o^2 , said spring pressing against the cam, substantially as and for the purpose described.

3. The outer sash, B, and inner sash, C, each pivoted to rope-socket pieces P at its lower 130 edge, the socket-pieces of the outer sash having a longer section below the pivotal point

than the socket-pieces of the inner sash, substantially as described.

4. The removable strips D and F, having their upper ends inclined, as described, in combination with the window-casing, and springs H, for holding the strips F, and spring-bolts I, for holding the strips D within the casing, substantially as and for the purpose described.

In testimony whereof I affix my signature in the presence of two witnesses.

JAN ZALIKOWSKI.
